UNITED STATES PATENT OFFICE.

ANDREW B. BARNARD, OF ST. JOSEPH, MISSOURI.

SEAL-LOCK.

SPECIFICATION forming part of Letters Patent No. 295,514, dated March 25, 1884.

Application filed November 3, 1883. (No model.)

To all whom it may concern:

Be it known that I, ANDREW B. BARNARD, a citizen of the United States, residing in St. Joseph, in the county of Buchanan and State 5 of Missouri, have invented a new and useful Improvement in Locks for Freight-Car Doors, of which the following is a specification.

This invention relates to the construction of that class of locks for freight-car doors consisting, essentially, of a bolt passing through the door into the wall of the car, or into the door opening, so as to engage with the door-post.

My object in the invention has been to render the bolt secure when in the locking position, and to simplify the device and its operation; and it consists in the novel construction and combinations of parts hereinafter set forth.

In the accompanying drawings, Figure 1 is a horizontal section of the door and adjacent part of the wall of a freight-car, showing the door open and unlocked. Fig. 2 is a similar view, with the door closed and locked. Fig. 3 is a horizontal longitudinal section of my improved lock, the bolt being in position ready for withdrawal in unlocking, or at the instant of insertion in locking. Figs. 4 and 5 are transverse vertical sections upon the line xx of Fig. 3, the first showing the bolt locked and the 30 second showing it in the same position as in Fig. 3. Fig. 6 is a front view of the invention; and Fig. 7 is a side view of the same.

In the drawings, A represents the door-opening; $A' A''$, the door-posts, and A^3 the door of an ordinary freight-car. Near the side edge of the door my improved lock is applied; and it consists of a barrel, B, adapted to be inserted in the door, and to pass from the outside to the inside thereof, and of uniform diameter, except at its outer end, b, where it is made smaller to conform to and afford a bearing for the shaft or central portion, c, of the bolt C, which slides and oscillates in said barrel, and also to form a shoulder which will engage with the feather 45 c' upon the shaft of the bolt and prevent the bolt being pulled out when in the locking position; and still further, to form a stop to engage with the enlarged inner end, c'' , of the bolt, and prevent its being withdrawn any 50 farther than is necessary to unlock the door. This shoulder b is of course slotted at one point,

b', to permit the passage of the feather c'. The inner end, c'' , corresponds in diameter to the main bore of the barrel, thereby affording the bolt a close bearing at that end. At its outer end the bolt carries a projection in the form of an eye, C', by means whereof it may be turned in the barrel and pushed into or pulled out of locking engagement. The major part of said eye lies at one side of the axis of the bolt, and aids as a weight in its oscillation. Surrounding and formed upon the barrel at the outer end is the face-plate or disk D, and upon this disk is cast the outstanding vertical eye or loop d. This loop is so located that when the bolt 60 is pushed in to lock the door the eye C' will lie adjacent to it; and the bolt may then be secured by passing the hasp of a padlock through said loop and eye, or by passing a sheet metal or wire seal through them in a similar manner. 65 An instance of this use of a sheet-metal seal, G, the ends whereof are eyeleted together at g, is illustrated in the drawings; and, as it is a matter of very great convenience to the trainmen that these seals, which serve also as designation-tags, should be so attached that they 70 may be read without being handled and positioned every time they are inspected, I provide the outer edges of the loop d, or of the eye C', or the outer edges of both, with shoulders 75 f, which will sustain the seal in a horizontal position parallel to the car side, as illustrated in Fig. 6. The initials of the road and the number of the station to which the car is destined may be stamped upon the metal of the 80 seal, and thus rendered plainly visible.

When the barrel and face-plate are made in two parts, as in the drawings, the dividing-line being indicated by m, I provide one of the parts with Δ projections n upon one of the 85 abutting faces registering with V -cavities in the other part, so that when inserted snugly in the door, and one of said parts is fastened to the door, as by the rivet o, the entire device is incapable of removal without destruction of 90 the rivet. The other part may or may not be riveted or screwed when this construction is adopted. These projections and cavities also insure accuracy of position when the parts are 95 assembled.

The loop d may be disconnected from the face-plate, and yet be similarly located paral-

lel to the bolt-eye; though I prefer to make it upon the plate.

I claim—

1. The barrel B, having the slotted shoulder *b*, the face-plate D, having the loop *d*, and the bolt C, having the feather, and the projecting eye C', all combined and operating substantially as specified.

2. In a car seal - lock, the combination of a bolt, C, entering the door from the outside, and having an outstanding eye, C', and an out-

standing loop, *d*, lying vertically parallel to said eye, said eye or loop, or one of them, being provided with shoulders *f*, upon their outer edge, whereby to support a tag-seal horizontally and parallel to the car side, substantially as and for the purpose specified. 15

ANDREW B. BARNARD.
